UNITED STATES PATENT OFFICE.

JOHN H. ALBRECHT, OF PITTSBURGH, PENNSYLVANIA, ASSIGNOR TO WESTINGHOUSE ELECTRIC AND MANUFACTURING COMPANY, A CORPORATION OF PENNSYLVANIA.

MOTOR-CONTROL SYSTEM.

1,360,257.

Specification of Letters Patent. Patented Nov. 30, 1920.

Application filed December 20, 1916. Serial No. 138,016.

To all whom it may concern:

Be it known that I, JOHN H. ALBRECHT, a citizen of the United States, and a resident of Pittsburgh, in the county of Allegheny and State of Pennsylvania, have invented a new and useful Improvement in Motor-Control Systems, of which the following is a specification.

My invention relates to motor-control systems and particularly to such systems as are employed in connection with blooming mills of the reversing type and similar machines.

My invention has for its object to provide an arrangement of the character above described whereby the operation of a plurality of electric motors may be selectively and successively effected.

A reversing blooming mill is usually provided with a front table for receiving ingots from the soaking pits and for delivering the ingots to the main rolls of the mill. A rear table receives the ingots after they have passed through the main rolls and returns the ingot to the rolls for the succeeding pass.

It has been the practice, to some extent, to provide the front and rear tables of blooming mills with a common driving mechanism by means of which the tables may be reversed simultaneously. It will be apparent that, during the operation of a mill thus constructed, one or the other of the tables will always be running idle. It is necessary, also, to reverse the driving motor and the tables as quickly as possible. This arrangement requires that the entire mechanism must be reversed each time the ingot passes through the rolls.

I provide an arrangement in which separate motors are provided for driving the front and rear tables. A single controlling mechanism operates either to effect the starting of one of the motors or of both the motors in succession, as desired. The mill may be operated by driving one table to carry the ingot to the roll while the table for receiving the ingot from the rolls may be stationary. In this case, it is only necessary to start the receiving table from rest instead of suddenly changing from full speed in one direction to full speed in the other direction. By means of this arrangement, a considerable saving in power is effected and a material amount of wear and

strain upon the motors and table mechanism is eliminated.

In the accompanying drawings, Figure 1 is a diagrammatic view of the main circuits of an electric motor for driving the front table of a blooming mill. Fig. 2 is a similar view of the main circuits of an electric motor for driving the rear table of a blooming mill. Fig. 3 is a diagrammatic view of the circuits for controlling the electric motors shown in Figs. 1 and 2. Fig. 4 is a schematic arrangement of the main circuits of one of the motors for driving the tables. Fig. 5 is a table illustrating the sequence of operation of the switches for controlling one of the motors.

Referring particularly to Fig. 1, an electric motor, the armature of which is indicated at 1 and which has a series field-magnet winding 2, may be employed to drive the front table of a blooming mill. The direction of rotation of the motor is controlled by electromagnetically-operable reversing switches 3, 4, 5 and 6 that are respectively provided with actuating coils 7, 8, 9 and 10.

A sectional starting resistor 12 is controlled by electromagnetically-operable switches 13, 14 and 15 that are respectively provided with series actuating coils 16, 17 and 18. A line switch 19, having an actuating coil 20, controls the main circuit of the motor.

Reference may now be had to Fig. 2, which is identical with Fig. 1. An electric motor, the armature of which is indicated at 22, and which has a series field magnet winding 23, may be operatively connected to the rear table of a blooming mill. The circuits of the motor 22 are controlled by switches that are identical with those described in connection with the motor 1 of Fig. 1 and they have been designated by the same reference numerals that are applied to the corresponding parts in Fig. 1.

Reference may now be had to Fig. 3 in which the circuits for controlling the switches shown in Figs. 1 and 2 are diagrammatically illustrated. A master switch, or controller 25 comprises an operating handle 26 and a single movable contact segment 27 for controlling the various circuits. When the controller handle 26 is in its illustrated or "off" position, the circuits of the several actuating coils of the reversing

switches and the line switches are open and the motors are at rest. In its "off" position, the contact segment 27 makes contact with two stationary contact fingers 30 and 30^a and the stationary contact finger 39. A circuit is accordingly established from the positive terminal of a manually-operable switch 29 through the contact finger 30, the contact segment 27, contact finger 39, conductor 38 and the actuating coil of the no-voltage relay 37 and an overload relay 31 of the motor 22 to the negative terminal of a manually-operable switch 35. The no-voltage relay 37 of the motor 22 is therupon closed and a circuit is established for the no-voltage relay 37 of the motor 1, which extends from the positive terminal of the switch 29 through the contact finger 30, the contact segment 27, the contact finger 39, the conductor 38, the no-voltage relay 37 and the overload relay 36 of the motor 22, the positive terminal of the switch 35, the actuating coil of the no-voltage relay 37 and the overload relay 31 of the motor 1 to the negative terminal of the switch 29. Holding circuits for the two no-voltage relays 37 are established as follows: from the positive terminal of the switch 35, which is connected to the positive terminal of the switch 29 by the overload relay 36 and the no-voltage relay 37 of the motor 1, through the overload relay 36 and the no-voltage relay 37 of the motor 22, the actuating coil of the relay 37 and the overload relay 31 of the motor 22 to the negative terminal of the switch 35; and from the positive terminal of the switch 29 through the overload relay 36, the no-voltage relay 37, the actuating coil of the relay 37 and the overload relay 31 of the motor 1 to the negative terminal of the switch 29. The overload relays 37 are thus closed in the "off" position of the controller 25 and are maintained closed by the above-described holding circuits subsequently to the actuation of the controller 25 unless opened by no-voltage or overload conditions.

When the handle 26 is actuated to the left, as viewed in Fig. 3, the contact segment 27 engages a contact finger 28 to complete a circuit which extends from the positive terminal of the switch 29, through the overload relay 36 and the no-voltage relay 37 of the motor 1, the positive terminal of the switch 35, the overload relay 36 and the no-voltage relay 37 of the motor 22, the conductor 38, the contact finger 39, contact segment 27, contact finger 28, actuating coils 8, 10 and 20 and overload relay 31 to the negative terminal of the switch 29. When the contact segment 27 engages the contact finger 28, it disengages the contact fingers 30 and 30^a. The actuating coils 8, 10 and 20 are energized to close the corresponding switches 4, 6 and 19 and thus complete the circuit

of the motor 1 for operation in the forward direction.

Referring particularly to Fig. 1, the main circuit of the motor 1, which is thus completed, extends from the positive terminal 70 of a switch 32, through overload relay coil 33, switch 6, armature 1, switch 4, series field magnet winding 2, actuating coil 16, resistor 12, switch 19, and coil 34 of overload relay 31 to the negative side of 75 switch 32.

The actuating coil 16 is energized by the circuit just described to close switch 13 and thereby shunt a section of the resistor 12 through the actuating coil 17 of switch 14. 80 The latter switch closes to complete a shunt circuit for a second section of the resistor 12 through the actuating coil 18 of switch 15. The switch 15 then completes a shunt circuit for the entire resistor 12 and the 85 motor 1 operates at full speed.

The front table now operates to carry the ingot to the rolls. After passing through the rolls, the ingot is deposited on the rear table. If it is so desired, the rear table may 90 be stationary when it receives the ingot, in which case the controller handle is permitted to remain in its first position in which the motor 1 only is operative.

If it is desired to operate the tables simultaneously, the controller handle 26 is actuated in the same direction to its second operative position. The contact segment 27 completes a circuit which extends from the positive terminal of manually operable control switch 35, which is connected, as above described, to the positive terminal of the switch 29, through overload relay 36, no-voltage relay 37, which occupies its closed position except upon failure of voltage, 100 conductor 38, contact finger 39, contact segment 27, contact finger 40, actuating coils 8, 10 and 20 of switches for controlling motor 22, and overload relay 31 to the negative terminal of switch 35. The motor 22 110 is then started in the same manner as that described in connection with motor 1. The motors 1 and 22 then operate simultaneously to drive the respective tables to which they are connected in the same direction. 115

When it is desired to return the ingot to the rolls, the table which has received the ingot is reversed. In the present case, the motor 22, which drives the rear table, is reversed by first actuating the controller 120 handle 26 to its "off" position to open the circuits of the several reversing switches for establishing the circuits of the motors for operation in the forward direction.

The controller handle is then actuated to 125 the right, as viewed in Fig. 3, opening the circuits controlled by the contact segment 27 and the contact fingers 30 and 30^a and completing a circuit which extends from the positive terminal of the switch 29 through 130

the overload relay 36 and the no-voltage relay 37 of the motor 1, the positive terminal of the switch 35, the overload relay 36 and the no-voltage relay 37 of the motor 22, the conductor 38, the contact finger 39, the contact segment 27, contact finger 42, actuating coils 7, 9 and 20 of switches for controlling motor 22, and overload relay 31 to the negative side of switch 35.

10 The circuits of motor 22 are then completed by the corresponding switches 3, 5 and 19 for operation of the motor and the rear table in the opposite direction. The ingot may be delivered to the front table 15 while the latter is stationary or the table may be operated in the same direction as the rear table, as desired.

To start the motor 1, it is only necessary to actuate the controller handle 26 to a second position and thus complete a circuit which extends from the positive terminal of switch 35, which is connected to the positive terminal of the switch 29, as described above, through overload relay 36, no-voltage relay 37, contact finger 39, contact segment 27, contact finger 43, actuating coils 7, 9 and 20 of switches for controlling motor 1, and overload relay 31, to the negative side of switch 29. The motor 1 is then 30 started and accelerated in the manner described above, and the front table is operated simultaneously with the rear table and in the same direction.

In case the currents traversing the series 35 actuating coils 34 and 33 of the overload relays 31 and 36 rise to predetermined values at which the relays are actuated to open their respective circuits, the relays will be retained in their open positions by reset devices 44 until the controller is again brought to its "off" position. When the controller occupies its illustrated position, the actuating coils 45 of the several reset devices 44 are energized by a circuit comprising the 40 contact finger 30^a and the reset devices are actuated to release the relays 31 and 36. This arrangement insures that the motors cannot be started except when the entire resistors 12 are in circuit.

50 It will be noted that, by means of the above-described arrangement, it is possible to render one of the motors operative while the other remains inoperative. The operator may, if he so desires, operate both motors simultaneously in the same direction. In the latter case, the motors are started successively by actuating the controller to its second operative position in the desired direction.

60 It is not necessary that the motors be

started simultaneously for the reason that the ingot is carried to the rolls by one of the tables only and the time required for the passing of the ingot through the rolls is sufficient to permit the motor driving the 65 table for receiving the ingot to accelerate to its normal speed. An advantage of this arrangement consists in the fact that the maximum power necessary for the successive starting of the motors is much less than 70 that required for the simultaneous starting of the motors.

I claim as my invention:

1. The combination with a pair of electric motors and a controller therefor adapted to occupy an inoperative position and a pair of operative positions, of a no-voltage relay for each of said motors, means for closing said relays when said controller occupies said inoperative position, means for 80 operating one of said motors when said relays are closed and said controller occupies one of said operative positions, and means for operating said other motor when said relays are closed and said controller occupies said other operative position.

2. The combination with a pair of electric motors and a controller therefor, of a no-voltage relay for each of said motors, means for closing said relays when said controller occupies one position, means comprising overload relays for maintaining said no-voltage relays closed except under predetermined conditions, means comprising said no-voltage relays for establishing circuits for said motors when said controller occupies other positions, and means for operating one or both of said motors in accordance with the position of said controller.

3. The combination with a pair of electric motors and a controller therefor, of a no-voltage relay for each of said motors, means for closing said relays when said controller occupies one position, means comprising overload relays for maintaining said no-voltage relays closed except under predetermined conditions, means for establishing a starting circuit for each of said motors when the said controller occupies other positions, 100 each of said starting circuits comprising one of said no-voltage relays and an additional overload relay and means for operating one or both of said motors in accordance with the position of said controller in either the forward or reverse directions.

In testimony whereof I have hereunto subscribed my name this 15th day of Dec., 1916.

JOHN H. ALBRECHT.
